WALL MOUNTED VANITY CABINET

Jean-Paul Dransart, Voiron, Isere, France, assignor to
Allibert Exploitation, Puteaux, Hauts-de-Seine, France

Filed July 23, 1973, Ser. No. 381,596

Claims priority, application France Jan. 23, 1973

Term of patent 7 years

Int. Cl. D6—04

U.S. Cl. D6—104

FIG. 1

FIG. 2

FIG. 3

FIG. 4

FIG. 5

FIG. 1 is a perspective view of the wall mounted vanity cabinet of the present invention;

FIG. 2 is an end elevational view thereof;

FIG. 3 is a front elevational view thereof;

FIG. 4 is a top plan view thereof; and

FIG. 5 is a bottom plan view thereof.

The back of the wall mounted vanity cabinet is substantially plain and flat.

I claim:

The ornamental design for a wall mounted vanity cabinet, as shown and described.
